(57) CLAIM

The ornamental design for a dispenser for a stethoscope personal protective equipment, as shown and described.

DESCRIPTION

FIG. 1 illustrates a perspective view of a dispenser for stethoscope personal protective equipment.

FIG. 2 illustrates a front view of the dispenser for stethoscope personal protective equipment.

FIG. 3 illustrates a left side view of the dispenser for stethoscope personal protective equipment. The right side view of the dispenser for stethoscope personal protective equipment is a mirror image.

FIG. 4 illustrates a rear view of the dispenser for stethoscope personal protective equipment.

FIG. 5 illustrates a top view of the dispenser for stethoscope personal protective equipment.

FIG. 6 illustrates a bottom view of the dispenser for stethoscope personal protective equipment.

FIG. 7 illustrates an environmental view of the dispenser for stethoscope personal protective equipment.

FIG. 8 illustrates a second environmental view of the dispenser for stethoscope personal protective equipment.

FIG. 9 illustrates a perspective view of an alternative embodiment of the dispenser for stethoscope personal protective equipment.

FIG. 10 illustrates a front view of the alternative embodiment of the dispenser for stethoscope personal protective equipment.

FIG. 11 illustrates a left side view of the alternative embodiment of the dispenser for stethoscope personal protective equipment. The right side view of the alternative embodiment of the dispenser for stethoscope personal protective equipment is a mirror image.

FIG. 12 illustrates a rear view of the alternative embodiment of the dispenser for stethoscope personal protective equipment.

FIG. 13 illustrates a top view of the alternative embodiment of the dispenser for stethoscope personal protective equipment.

FIG. 14 illustrates a bottom view of the alternative embodiment of the dispenser for stethoscope personal protective equipment.

FIG. 15 illustrates an environmental view of the alternative embodiment of the dispenser for stethoscope personal protective equipment; and,

FIG. 16 illustrates a second environmental view of the alternative embodiment of the dispenser for stethoscope personal protective equipment.

Broken lines are used to illustrate environmental subject matter that form no part of the claimed invention.
